United States Patent Office

Des. 214,085
Patented May 6, 1969

214,085

TWO-PIECE SQUEEGEE

William Fred Fremdling, West Los Angeles, Calif., assignor to Wefco Rubber Manufacturing Corp., a corporation of California

Filed June 12, 1968, Ser. No. 12,311

Term of patent 14 years

Int. Cl. D7—06

U.S. Cl. D49—23

FIG. 1.

FIG. 2.

FIG. 3.

FIG. 4.

FIG. 5.

FIGURE 1 is a perspective view of a two-piece squeegee showing my new design;

FIGURE 2 is a side elevational view thereof showing the side not visible in FIGURE 1;

FIGURE 3 is an end view thereof showing the end not visible in FIGURE 1;

FIGURE 4 is a top plan view thereof; and,

FIGURE 5 is a bottom plan view thereof.

I claim:

The ornamental design for a two-piece squeegee, substantially as shown.
